UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 19,819, dated May 6, 1890.

Application filed April 11, 1890. Serial No. 347,544. Term of patent 3½ years.

To all whom it may concern:

Be it known that I, JAMES L. FOLSOM, a citizen of the United States, residing in the city of Brooklyn, in the county of Kings and State of New York, have invented a new and original Design for Carpets, of which the following is a specification, reference being had to the accompanying photograph, which forms a part of the same.

10 The invention relates to a design to be worked into or upon surfaces, such as carpets or similar fabrics; and it consists in the novel configuration and grouping of figures herein specifically shown and claimed.

15 The accompanying photograph is a face view of a carpet showing my new design.

My design is composed of a body A and a border B.

20 The body A consists of irregular figures having an ornamentation resembling in appearance the grain of wood cut in cross-section. These figures are scattered over the design at irregular intervals. The groundwork consists of irregular line-work.

The border B has an inner margin of small 25 ornamental figures. Next to this is the main part of the border, which is similar in character to the body portion A of the design, and then an outer part irregular in form and having coral-shaped figures combined with small 30 circular flower forms. The outer margin has indistinct grain effects at irregular intervals.

What I claim as new, and desire to secure by Letters Patent, is—

1. The design for a carpet, consisting of the 35 body A, substantially as shown.
2. The design for a carpet, consisting of the border B, substantially as shown.
3. The design for a carpet, consisting of the 40 body A and the border B, substantially as shown.

JAS. L. FOLSOM.
